(57) **CLAIM**

The ornamental design for a baby bottle as shown and described.

DESCRIPTION

FIG. 1 is an upper front perspective view of the baby bottle, according to my design in a first configuration with the cap on the top of the bottle;

FIG. 2 is a front elevation view thereof;

FIG. 3 is a back elevation view thereof;

FIG. 4 is a right side elevation view thereof;

FIG. 5 is a left elevation view thereof;

FIG. 6 is a top plan view thereof;

FIG. 7 is a bottom plan view thereof;

FIG. 8 is an upper front perspective view of the baby bottle, according to my design in a second configuration with the cap on the bottom of the bottle; and,

FIG. 9 is a front elevation view of the baby bottle of FIG. 8 in the second configuration.

The broken line features are text and surface markings that form no part of the claimed design. The lid and bottle body are shown as transparent.

1 Claim, 8 Drawing Sheets
